(57) **CLAIM**

The ornamental design for a wheel alignment optical target as shown and described.

DESCRIPTION

FIG. 1 is a top perspective view of a wheel alignment optical target;

FIG. 2 is a bottom perspective view of the wheel alignment optical target;

FIG. 3 is a top view of the wheel alignment optical target;

FIG. 4 is a bottom view of the wheel alignment optical target;

FIG. 5 is front view of the wheel alignment optical target;

FIG. 6 is a rear view of the wheel alignment optical target;

FIG. 7 is left side view of the wheel alignment optical target;

and,

FIG. 8 is right side view of the wheel alignment optical target.

The broken lines shown within the drawings illustrate features that form no part of the claimed design.
